(57) **CLAIM**

The ornamental design for an optical scanner, as shown and described.

DESCRIPTION

1.-3. Optical scanner

Fig. 1.1 is a back view of the first embodiment of an optical scanner according to the present invention;

Fig. 1.2 is a left side view of the optical scanner;

Fig. 1.3 is a bottom view of the optical scanner;

Fig. 1.4 is a front view of the optical scanner;

Fig. 1.5 is a right side view of the optical scanner;

Fig. 1.6 is a perspective view of the optical scanner;

Fig. 1.7 is a top view of the optical scanner;

Fig. 2.1 is a folded perspective view of a second embodiment of the optical scanner;

Fig. 2.2 is an unfolded perspective view of the optical scanner;

Fig. 3.1 is a front view of a third embodiment of the optical scanner;

Fig. 3.2 is a back view of the optical scanner;

Fig. 3.3 is a left side view of the optical scanner;

Fig. 3.4 is a bottom view of the optical scanner;

Fig. 3.5 is a right side view of the optical scanner;

Fig. 3.6 is a perspective view of the optical scanner; and

Fig. 3.7 is a top view of the optical scanner.
